J. L. McKEOWN

BENDING AND CLAMPING FRAME

Filed Feb. 15, 1924

UNITED STATES PATENT OFFICE.

JOHN L. McKEOWN, OF WINNETKA, ILLINOIS.

BENDING AND CLAMPING FRAME.

Application filed February 15, 1924. Serial No. 693,053.

To all whom it may concern:

Be it known that I, JOHN L. McKEOWN, a citizen of the United States, and a resident of Winnetka, in the county of Cook and State of Illinois, have invented an Improved Bending and Clamping Frame, of which the following is a specification.

This invention relates to bending and clamping frames, and relates particularly to frames designed and adapted for fabricating unitary, laminated wood structures of fixed curvatures.

Specifically, my invention relates to a frame particularly designed and adapted for fabricating the bowed top chords of wood trusses, consisting of a plurality of superposed pieces of lumber bent to proper curvature and glued together.

The object of the invention is to provide a frame for the purpose specified, by means of which laminated wood structures—particularly the laminated top chords of wood trusses—may be fabricated expeditiously and economically, and which may readily be adjusted for fabricating structures having different radii.

To effect the objects of the invention, my improved bending and clamping frame comprises a plurality of units, all of which are substantially duplicates of each other, and each of which comprises a base or stringer member adapted to be disposed horizontally, and a post member supported in upright position upon said base member and extending at right angles thereto.

Both the stringer and post members of said units will preferably be formed from channel beams secured together in spaced relation, the channels forming the base members being disposed outwardly and of the post members being disposed inwardly.

To provide for varying the curvature of the arc defined by my improved bending and clamping frame, the lower ends of the post members of the different units have sliding engagement with the base members thereof, and are adapted to be rigidly connected to said base members at a distance from what, for convenient reference, may be designated their front ends, by bolts adapted for clamping brackets secured to said post members thereto, said clamping bolts preferably extending through the slots in said base members between the spaced channel bars forming

the same and the heads of said clamping bolts engaging beneath the lower edges thereof. As shown, the lower ends of the post members are slidably connected to the base members by clips secured to said post members, the ends of which are bent inwardly beneath the upper flanges of the channel beams forming said base members.

Said post members are also supported by means of diagonal shores or braces, which connect said post members at points adjacent to their upper ends, with said base members, at points adjacent to their rear ends. Preferably, also, said shores or braces are adjustably connected to the base members, thus providing convenient means for truing up said post members relative to the base members when erecting the units for use.

Each unit of my improved bending and clamping frame also comprises clamping means adapted for holding the pieces of lumber to be joined firmly in contact with the post members of said unit and also with each other, whereby they may be bent to conform to the arc defined by said bending and clamping frame and will be held firmly in contact with each other until glue applied thereto sets and hardens sufficiently to insure that the laminated structure formed thereby will be firmly connected and will retain its curvature, forming in effect a substantially unitary structure.

Desirable clamps for the purpose specified consist of bolts, the heads of which engage the T-slot formed by the spaced front flanges of said post members and which project frontwards therefrom, the lengths of said bolts being proportioned to the maximum radial dimension of the laminated structure which the frame is designed for fabricating. Said clamp also comprises a clip portion adapted to engage the outer sides of the pieces of lumber being bent and applied, and nuts threaded to the ends of said clamping bolts outside of said clips, adapted for subjecting the pieces of lumber to desired pressure to bend and clamp them firmly together until the glue is set.

In use, the base members of the different units are supported on a suitable flat foundation, a desirable and preferable foundation consisting of sills laid on a floor or other suitable flat surface, which extend trans-

versely of said base members, being preferably bent or bowed to provide for using base members of the same length for different units. In use, also, the different units are erected so that the base members extend substantially radially of the arc of the structure being fabricated and are spaced relatively short distances apart, say from 18 inches to 24 inches between centers at the 10 post members.

As shown, each clamp is adapted for simultaneously engaging two different structures, and the height of the post members may be proportioned for simultaneously 15 utilizing any desired number of clamps, thus providing for simultaneously fabricating a corresponding number of such laminated structures on the same frame.

A combined bending and clamping frame 20 of my invention also comprises the various other features, combinations of features and details of construction hereinafter described and claimed.

In the accompanying drawings in which 25 my invention is fully illustrated,

Figure 1 is a fragmentary top plan view of a bending and clamping frame embodying my invention and improvements, showing a bowed, laminated top cord section 30 therein in process of fabrication.

Figure 2 is an enlarged front end view of one of the units of said frame erected for use.

Figure 3 is a side view of said unit, showing 35 two chord sections clamped therein; and

Figure 4 is a fragmentary view similar to Fig. 2 illustrating the manner of using my improved frame for fabricating more than two chord sections.

40 For purposes of clear and definite illustration, I have, in the accompanying drawings shown a bending and clamping frame embodying my invention and improvements as applied in use for fabricating sections 45 of the bowed top chord of a truss, designated as a whole A, consisting of a plurality of pieces of lumber a bent to a desired curvature and rigidly secured together to form a unitary, laminated structure.

50 The pieces of lumber a will preferably be glued together, although my invention contemplates the use of any desired or approved means for this purpose.

Describing my improved bending and 55 clamping frame with particular reference to the drawings, said frame, designated as a whole B, comprises a plurality of separate units each designated as a whole B¹. All of said units are duplicates of each other 60 and a description of one thereof will apply equally to all, and the accompanying description is, therefore, in the singular.

In the drawings, in which I have shown in detail a single unit of my improved bending 65 and clamping frame on an enlarged scale,

each unit B¹ comprises a base member B² which, in use, is disposed horizontally, and an upright or post member B³ the lower end of which is adapted to be secured to said base member at a distance from what for 70 convenient reference, may be designated its front end, preferably, in such manner that it may be adjusted lengthwise thereof.

Both the base member B² and the post member B³ are made of steel channel beams 75 1 rigidly secured together in spaced relation, the flanges of the beams forming the base member being disposed outwardly and those of the post member being disposed inwardly. Simple means for connecting said 80 channel beams consists of bolts 2 inserted through holes formed in the webs of said channels and spacing sleeves 3 placed over said bolts between the webs of the connected beams. 85

To provide for quickly and conveniently varying the position of the post member B³ on the base member B², the lower end of said post member is slidably connected to said base member and is adapted to be rigidly 90 means of a clamping bolt 4, which extends secured in adjusted position thereon by through a hole formed in an angle or bracket 5 secured to the rear side of said post member and downwardly through the slot 6 95 defined by the webs of the channels 1 forming said base member, the head of which interlocks with the lower edges of said channels, and which is tightened from above.

As shown, the lower end of the post member B³ is confined upon the base member B² by means of clips 7 secured to opposite sides of said post member, the lower ends of which are bent inwardly so as to hook under the top flanges of the channels which 100 form said base member, as shown at 8.

The post member B³ is supported in upright position by means of a shore or brace 9 secured to said post member adjacent to its upper end, preferably in such manner 110 that it may quickly and conveniently be attached thereto and detached therefrom, as by means of bolts, and the opposite end of which is secured to the base member adjacent to its rear end, preferably by means 115 of a clamping bolt 10, affording means for truing up said post member with reference to said base member so that its front face will extend substantially at right angles to the top side of said base member. 120

As shown, the shore or brace 9 consists of a section of T-bar, opposite ends of which are flattened so as to rest against the rear and upper faces of the post and base members, respectively. 125

Each of the units B¹ also comprises clamping means, designated as a whole C, adapted for drawing the inner pieces of lumber a into contact with the post member B³, which define the curvature of the structure, and 130

succeeding pieces into contact with each other. Thus, by applying glue to the inner surfaces of the pieces of timber as they are applied, excepting the piece first applied, glued joints will be formed between outer pieces *a* and adjacent inner pieces, and, when the full number of pieces of lumber have been applied, will afford means for clamping said pieces of lumber together until the glue sets and hardens sufficiently to hold the entire structure to fixed curvature.

What I now consider to be a preferable form of clamp, comprises a clip 11 adjusted to a bolt 12 the end of which is secured in the T-slot 13 formed by the spaced front flanges of the channels 1 forming the post member *B*³, and a nut 14 threaded to the end of the bolt 12 outside of the clip 11, which affords means for advancing said clip 20 towards the post member *B*³.

As shown, the clip 11 is double-ended, thus providing for simultaneously fabricating two truss sections *A*, or other laminated structures.

Also, the post members *B*³ are made of sufficient height or length to provide for simultaneously fabricating any desired number of laminated truss sections *A* or other laminated structures, the limitation in this respect being the height or elevation at which the work can be performed conveniently and expeditiously.

In process of fabrication, the lowermost truss section *A* or other laminated structure, will rest directly upon the projecting front ends of the base members *B*² and, where the pieces of lumber *a* are glued together—as preferably contemplated—superposed structures will be supported in spaced relation to those immediately beneath them by thin spacing strips 15, see Fig. 4, thus preventing them from becoming glued together, as might otherwise happen.

As erected for use, a frame *B* of my invention comprises any desired number of units *B*¹ supported in spaced relation to each other, a desirable spacing for usual purposes being from 18 inches to 24 inches between centers of adjacent units at the posts *B*³. This relation may, however, vary with the thickness and stiffness of the pieces of lumber *a*.

The units *B*¹ will preferably be erected for use upon a suitable foundation, the top of which defines a flat surface. A desirable form of foundation consists of sills 16 secured to a floor, the line of which is indicated at 17, or other suitable surface. The units are arranged with the base members *B*² extending substantially radially of the mean arc of the structures which the frame is designed for fabricating, the sills 16 extending transversely of said base members *B*² and preferably conforming substantially to the mean curvature of said structure,

thus providing for the use of base members *B*² of the same length for all of the units *B*¹. In use the base members of the units *B*¹ will be bolted or otherwise rigidly secured to the sills 16.

In erecting or adjusting the frame for use, the post members *B*³ will be secured to the base members *B*² at a distance from their front ends in proper position to define the curvature of the truss section *A* or other laminated structure which is to be fabricated, after which the shores or braces 9 are adjusted to bring the front faces of the post members *B*³ perpendicular to the top sides of the base members *B*².

As previously stated, my improved bending and clamping frame is particularly designed and adapted for fabricating the bowed top chords of wood trusses, consisting of a plurality of superposed pieces of lumber bent to proper curvature and glued together, and I will now describe my improved frame as utilized for this purpose.

In fabricating such chords, the contacting sides of the pieces of lumber *a* are preferably dressed. The pieces of lumber forming a section of a top chord are then placed in the frame with their lower edges resting upon the projecting front ends of the base members *B*², glue being applied to the inner sides of each piece of lumber, excepting the first or inner piece. The full number of pieces, (as shown five) having been placed in the frame, clamps *C* are applied thereto and the pieces of lumber *a* forming another truss section are, in like manner, placed in the frame, being spaced from the pieces forming the first section of the truss by spacing strips 15, which are slightly thicker than the diameter of the clamping bolts 12, said spacing strips preventing the adjacent edges of said truss sections from becoming glued together.

After the pieces forming both truss sections have been placed in the frame, the clamping nuts 14 are tightened so as to draw the pieces of lumber *a* forming both truss sections into close contact, with the inner surfaces of the inner pieces resting against the post members *B*³ of the frame. The structure is then permitted to stand for a sufficient length of time for the glue to set and harden so as to permanently connect the pieces of lumber *a* and impart a permanent bow or curvature to the structure. The clamps are then removed and the truss sections are ready to be embodied in the finished truss.

In like manner any contemplated number of truss sections may be formed in the same frame, the limitation in this respect being the distance from the floor or supporting surface at which the work can be formed quickly and economically.

In setting up the clamping nuts 14, an

4 electrically operated wrench will be employed initially, thus providing for turning the nuts up rapidly, final tightening of the nuts being preferably effected by means of 5 powerful hand wrenches, insuring tight joints and close contacts between adjacent pieces *a*.

In the case of trusses or other structures 10 which are relatively stiff and hard to bend, either on account of the number of pieces 15 *a* or their size or the lumber used, the clamping nuts 14 may be set up a little at a time instead of all at one time.

To prevent turning of the bolts 12 while 15 the nuts are being tightened, they are preferably squared under the heads, as shown at 18, said squared portion fitting loosely into the slots in the post members *B*³ through 20 which the bolts 12 extend.

20 I claim:

1. A bending and clamping frame consisting of a plurality of units, each comprising a fixed base member and a separate post member, means for supporting said 25 post member in upright position on said base member, and clamping means in association with said post member, said units as erected for use being arranged so that the post members thereof will define the 30 shape of the structure to be formed thereon.

2. A bending and clamping frame as specified in claim 1, in which the post members are positioned at a distance from the 35 ends of the base members to which they are secured, respectively, the projecting ends of said base members forming a support for the pieces to be bent.

3. A bending and clamping frame as 40 specified in claim 1, in which the post members of different units are separately adjustable endwise of their respective base members.

4. A bending and clamping frame as 45 specified in claim 1, in which the means for supporting the post members is constructed and arranged for truing up said post members with their respective base members.

5. A bending and clamping frame as 50 specified in claim 1, in which the means for supporting the post members on their respective base members comprise shores or braces which connect the base and post members of the different units.

6. A bending and clamping frame as 55 specified in claim 1, in which the means for supporting the post members on their respective base members comprise shores or braces which connect the base and post members of the different units, and the 60 means for connecting the shores to the base and post members to which they are applied is constructed and arranged for connecting said shores to one thereof at different points lengthwise thereof.

65 7. A bending and clamping frame as

specified in claim 1, in which the lower ends of the post members are slidably connected to their respective base members.

8. A bending and clamping frame as 70 specified in claim 1, in which the lower ends of the post members are slidably connected to their respective base members, said slideable connection comprising clips on the lower ends of the post members which hook beneath flanges on the base members. 75

9. A bending and clamping frame as specified in claim 1, in which the lower ends of the post members are slidably connected to their respective base members, said connecting means comprising means for detachably connecting the lower ends of the post members rigidly to their base members. 80

10. A bending and clamping frame as specified in claim 1, in which the base and post members consist of channel beams rigidly secured together in spaced relation. 85

11. A bending and clamping frame as specified in claim 1, in which the base and post members consist of channel beams rigidly secured together in spaced relation, the 90 flanges of the channels forming the base members being disposed outwardly.

12. A bending and clamping frame as specified in claim 1, in which the base and post members consist of channel beams rigidly secured together in spaced relation, the flanges of the channels forming the post 95 members being disposed inwardly.

13. A bending and clamping frame as 100 specified in claim 1, in which the post members are provided with longitudinal T-slots and the clamping means associated therewith comprises anchor bolts the heads of which are secured in the T-slots formed in said post members respectively, clips adjusted to said anchor bolts, and nuts threaded to said bolts outside of said clips. 105

14. A bending and clamping frame as specified in claim 1, in which the post members are provided with longitudinal T-slots and the clamping means associated therewith comprises anchor bolts the heads of which are secured in the T-slots formed in said post members respectively, double-ended 110 clips adjusted to said anchor bolts, and nuts threaded to said bolts outside of said clips. 115

15. A bending and clamping frame as specified in claim 1, in which the different units are erected on a suitable foundation, the base members of the different frame units being disposed substantially radially to the arc of the structure to be fabricated. 120

16. A bending and clamping frame as specified in claim 1, in which the different units are erected on a foundation consisting of sills secured to a floor or other flat surface which extend transversely of the base members of the frame units. 125

17. A bending and clamping frame as 130

specified in claim 1, in which the different units are erected on a foundation consisting of curved sills secured to a floor or other flat surface which extend transversely of the 5 base members of the frame units.

18. A bending and clamping frame as specified in claim 1, in which the post members of the frame are proportioned to

adapt the machine for simultaneous bending and clamping more than two pieces on said 10 frame and each of the units of said frame comprising a plurality of clamping means.

In witness that I claim the foregoing as my invention, I affix my signature this 7th day of February, A. D. 1924.

JOHN L. McKEOWN.
